US0D1075679S

(12) **United States Design Patent** (10) **Patent No.:** **US D1,075,679 S**
(45) **Date of Patent:** **** May 20, 2025**

(54) **ELECTRICAL CONNECTOR**

(71) Applicants: **Norman R. Byrne**, Ada, MI (US);
Shane Rogers, Rockford, MI (US);
Patrick E. Young, Grand Rapids, MI (US); **Randell E. Pate**, Jenison, MI (US)

(72) Inventors: **Norman R. Byrne**, Ada, MI (US);
Shane Rogers, Rockford, MI (US);
Patrick E. Young, Grand Rapids, MI (US); **Randell E. Pate**, Jenison, MI (US)

(73) Assignee: **Norman R. Byrne**, Ada, MI (US)

(**) Term: **15 Years**

(21) Appl. No.: **29/660,274**

(22) Filed: **Aug. 20, 2018**

(57) **CLAIM**

The ornamental design for an electrical connector, as shown and described.

DESCRIPTION

FIG. 1 is a top perspective view of an electrical connector showing our new design;

FIG. 2 is a bottom perspective view thereof;

FIG. 3 is a front end elevation thereof;

FIG. 4 is rear end elevation thereof;

FIG. 5 is a right side elevation thereof;

FIG. 6 is a left side elevation thereof;

FIG. 7 is a top plan view thereof;

FIG. 8 is a bottom plan view thereof;

FIG. 9 is a top perspective view of another electrical connector showing our new design;

FIG. 10 is a bottom perspective view thereof;

FIG. 11 is a front end elevation thereof;

FIG. 12 is rear end elevation thereof;

FIG. 13 is a right side elevation thereof;

FIG. 14 is a left side elevation thereof;

FIG. 15 is a top plan view thereof; and,

FIG. 16 is a bottom plan view thereof.

The Dash-Dash broken line represents the portions of the article that form no part of the claimed design. The Dash-Dot broken line represents the claim boundary and form no part of the claimed design.

1 Claim, 4 Drawing Sheets

Related U.S. Application Data

continuation-in-part of application No. 11/747,518, filed on May 11, 2007, now abandoned.
